UNITED STATES PATENT OFFICE.

JOSEPH S. THOMPSON, OF SAN FRANCISCO, CALIFORNIA.

ELECTRIC SWITCH.

Application filed May 11, 1925. Serial No. 29,282.

To all whom it may concern:

Be it known that I, JOSEPH S. THOMPSON, a citizen of the United States, residing in the city and county of San Francisco, State of California, have invented a certain new and useful Electric Switch, of which the following is a specification.

The invention relates to electric switches. More particularly it relates to disconnecting switches of the knife or blade type, and has for its object the provision of an improved switch of this character whereby a complete and efficient contact may be secured between the blade and the switch contacts.

15 An object of my invention is to provide contacting means arranged to engage between the forks of a bifurcated switch blade, or a blade having two spaced plates, which means are self-aligning so as to secure a 20 complete contact.

Another object of my invention is to provide a switch having contacting means of the character described which means are compressible so that when the switch is 25 closed, said means will tightly hold the blade in its closed position as well as clamp the forks of said blade between itself and the adjacent contacts to secure a complete and efficient contact.

30 The invention possesses other advantageous features, some of which with the foregoing will be set forth at length in the following description, where I shall outline in full that form of the invention which I have 35 selected for illustration in the drawings accompanying and forming part of the present specification. In said drawings I have shown one form of device embodying my invention, but it is to be understood that I 40 do not limit myself to such form, since the invention as set forth in the claims may be embodied in a plurality of other forms.

In the drawings:

45 Figure 1 is a vertical sectional view of a switch embodying my invention; and

Fig. 2 is a perspective view with parts shown in section illustrating details shown in Fig. 1.

50 Referring to the drawings in which 1 indicates a switch base, which is provided with a pair of contacts or shoes 2, 2'. The contact 2 is resiliently supported by a spring 3 within an extension or housing 4 formed on the base 1 and is clamped or secured to said base by means of a bolt 5 as shown. The contact 2' is supported in a similar manner

by corresponding parts which are given similar reference numerals primed. Said contacts 2, 2' are electrically connected with the base 1 by flexible conductors 6, 6' respectively. It is of course understood that the base is of conducting material adapted to be mounted on an insulating panel. Intermediate the contacts 2, 2' is positioned my improved contact element which consists of two plates 7, 8. These plates are secured to the base 1 by the bolt 5, which passes through an enlarged opening near the base of the same, as best shown in Fig. 2, so as to permit a limited vertical as well as an axial 60 movement of the plates thereon for adjusting or self-aligning purposes, in a manner readily understood. The plates therefore have a bodily movement which insures parallelism and therefore complete surface contact. The plates 7, 8 are each secured at their bases by similar members 9 to flexible conductors 11, 12 respectively, these conductors also being secured to the base 1 in the same manner as conductors 6, 6' are. At 65 their upper ends, the plates 7, 8 are respectively provided with right and left hand interlocking projections 13, 14 which while permitting the blades to move toward each other, limit the distance they may separate. 70 Between the plates 7, 8 are two steel springs 15, 16 which are bent to react against each other. These springs are held on the base by the bolt 5, and their lower ends are retained in a groove 17 in the base 1. Their 75 upper ends engage the inner surfaces of plates 7, 8 and tend to urge the same apart, thus forming a compressible contact element between the shoes 2, 2'. With my invention, I employ a switch blade having two plates 80 18, 19. It is of course understood that the switch blade may consist of two spaced plates or it may consist of a single bifurcated blade and it is to be understood that the term bifurcated is intended to apply to either type of construction. Preferably the 85 lower edges of the switch blade are rounded as shown. Likewise, the interlocking projections 13, 14 are rounded, so that the switch blade may readily pass over the same. 90 When the switch is closed, as shown in Fig. 1, the plates 7, 8, due to their loose mounting on bolt 5, are free to align themselves, and due to the action of springs 15, 16 tightly engage the forks or parts 18, 19 of the switch blade, thereby holding the same in closed 95 position and making a complete contact.

The plates 18, 19 are also in complete contact with shoes 2, 2', due to their resilient mounting. It is of course understood that the several contacting surfaces have been machined to secure the best contact.

What I claim and desire to secure by United States Letters Patent is:

1. In an electric switch, a pair of spaced contacts, and a contact element intermediate 10 said spaced contacts comprising two adjacent plates, means between the same normally urging said plates apart and means limiting the separation of the same said plates being supported to permit a limited 15 vertical and horizontal movement.
2. An electric switch comprising a bifurcated switch blade, spaced contacts adapted to make contact with the outer surfaces of said blade and means for making contact 20 between the forks of said blade comprising two blades having interlocking projections permitting a limited separation of said blades and resilient means tending to separate said blades.
3. An electric switch comprising a bifurcated switch blade, spaced contacts adapted to make contact with the outer surfaces of said blade and contacting means adapted to engage between the forks of said blade comprising two plates loosely supported at their 25 lower parts to permit self-alignment, said plates having interlocking means at their upper ends to permit a limited separation of said blades and resilient means between 30 said plates normally urging the same apart.
4. An electric switch comprising a bifurcated switch blade, resiliently supported 35

spaced contacts adapted to make contact with the outer surfaces of said blade and contacting means adapted to engage between 40 the forks of said blade comprising two plates loosely supported at their lower parts to permit self-alignment, said plates having interlocking means at their upper ends to permit a limited separation of said blades and resilient means between 45 said plates normally urging the same apart.

5. An electric switch comprising a bifurcated switch blade, resilient mounted spaced contacts adapted to engage the outer surfaces of said blade, and resilient contact means adapted to urge the forks of said blade against the adjacent contact said means being loosely supported to permit 50 self-alignment.

6. An electric switch comprising a bifurcated switch blade, spaced contacts adapted to make contact with the outer surfaces of said blade and a compressible contact element adapted to make contact with the inner surfaces of said blade, said element being loosely supported to permit a limited 60 vertical and horizontal movement.

7. An electric switch comprising a bifurcated switch blade, spaced contacts adapted to engage the outer surfaces of said blade, and resilient contact means adapted to urge the forks of said blade against the adjacent contact, said means being loosely supported 65 to permit a limited vertical and horizontal movement.

In testimony whereof, I have hereunto set my hand.

JOSEPH S. THOMPSON.
